ELECTRICAL PAD HEATERS

Malcolm W. Patrick, Bedford, Ohio, assignor to Hupp Corporation, Cleveland, Ohio, a corporation of Virginia

Filed Aug. 22, 1961, Ser. No. 133,242

1 Claim. (Cl. 219—19)

This invention relates to electrical pad-type heating devices and more particularly to such devices for use out of doors or in other exposed environments where they are subjected to the effects of moisture, dirt and temperature variations.

While heaters of the present invention are of general application, it has been found that they are particularly well-suited for use in connection with heat pumps. As is well known in the art, heat pumps comprise indoor and outdoor coils reversibly connected by a closed refrigerant system to permit operation of the unit for heating or cooling.

When a heat pump is used on the heating cycle, the outdoor coil assembly functions as the evaporator. When, as is often the case, the outdoor ambient temperature is below freezing, there is a tendency for frost to form on the outdoor coils at an accelerated rate and for condensate to freeze in the sump of the unit. In one application the pad-type heaters of the present invention are installed in the condensate sump and are effective to prevent freezing of the water in the sump and the other objectionable conditions which arise upon operation of such units under low ambient temperatures. The pad heaters of the present invention are particularly suited for such application since they are structurally rugged, completely water-proof and impervious to environmental factors which heretofore prevented the trouble free operation of such units under comparable severe service conditions.

With these considerations in mind it is the principal purpose and object of the present invention to provide novel electrical pad heaters which have an extended trouble-free service life even under the most unfavorable service conditions.

It is a further object of the present invention to provide improved electrical pad heaters which are completely impervious to the effects of moisture, ice or dirt, and thus are particularly well-suited for operating in exposed outdoor locations.

It is an additional object of the present invention to provide improved electrical pad heaters which have sufficient mechanical strength to resist damage by impact.

It is a further object of the present invention to provide electrical pad heaters which have an unusually large heating capacity for given size and which are inexpensive to manufacture.

In attaining these and other objects, the heaters of the present invention include a length of resistance wire imbedded in an insulating plastic envelope and enclosed in an outer sealed metal envelope of novel configuration which imparts structural rigidity to the entire assembly, and novel means for connecting the interior resistance wires to the exterior of the device to positively seal the entire heater assembly and to prevent mechanical damage to the wires.

Additional objects and advantages will become apparent as the description proceeds in connection with accompanying drawings in which:

FIGURE 1 is a top plan view of the heater of the present invention;

FIGURE 2 is an elevation of the unit of FIGURE 1;

FIGURE 3 is a section taken along line 3—3 of FIGURE 1;

FIGURE 4 is an enlarged fragmentary view of the

2

inner plastic envelope as it appears before it is enclosed in the outer metal housing and;

FIGURE 5 is an enlarged fragmentary section taken along line 5—5 of FIGURE 4.

5 Referring now more particularly to the drawings, the heater of the present invention has been illustrated in a rectangular configuration particularly suited for use as a sump heater for a heat pump unit. However, it is to be understood that the pad can assume other configurations as required by the needs of a particular installation.

Two principal components of the heater assembly are the outer thin metal envelope, indicated generally at 20, and the inner plastic heater assembly, indicated generally at 22, shown separately in FIGURES 4 and 5 to which detailed reference will now be made.

The assembly 22 comprises upper and lower sheets 24 and 26 of neoprene or a similar flexible insulating material, between which is received a continuous length of insulated wire 28. As shown in FIGURE 4 the terminal ends 30 and 32 of the wire 28 are positioned adjacent one corner of the unit and project laterally of the unit. The portion of the wire extending away from the terminal 30 proceeds across the end of the unit and then is formed into a series of reverse U-bends 34 and 36 adjacent the ends of the unit to form a plurality of parallel lengths extending between the ends of the unit. The wire leading from the terminal 32 is provided with a reverse U-bend 38 from which it extends to the front edge of the assembly. Preferably the wire 28 has sufficient stiffness so that once it is bent into the configuration shown in FIGURE 4, it tends to remain in this configuration thus avoiding the imposition of elastic stress on the flexible insulating sheets 24 and 26.

In the manufacture of the unit the entire length of wire is first bent to the final configuration shown in FIGURE 4, the insulation is removed from the terminal portions of the wire and the ends of the power supply lines 40 and 42 are wrapped securely around these terminal portions. The wires are silver soldered and wrapped with electrical tape. The upper surface of the lower insulating sheet 26 and the entire wire grid are coated with a suitable cement such as cement sold under the trademark Pliobond, and the wire grid is positioned on the lower sheet 26. After the main power cables 40 and 42 are passed through a slit 44 in the upper sheet 24, the upper sheet is carefully pressed onto the lower sheet and the wire grid with the edges of the sheets matched. As shown in FIGURE 5, the sheets are pressed together between the lengths of wire 28 to form a permanent bond between the upper and lower sheets which extends over substantial surface area. To insure adhesion of the upper and lower insulating sheets 24 and 26, short pieces of electrical tape 48 are firmly pressed into place at the corners 55 of the unit and along the edges of the unit. An additional piece of tape 50 is installed between the sheets 24 and 26 in the region of the terminal portions of the wire 28. To provide further insulation in the region of the connection between the wire 28 and the main power leads 40 and 42, a piece of electrical tape 51 is installed in this area.

The outer metal housing or envelope 20 is formed from a single thin sheet of metal, preferably thin gauge steel. After the sheet is cut to size which is approximately the same length as the final assembly and twice the width, the sheet is stamped to form a central dish-shaped embossment 52 surrounded by a flat marginal flange 54. A cup-shaped embossment 56 is also formed at this time adjacent one corner of the sheet. A tube 58 is then brazed to the embossment 56. The housing is then partially folded over on itself, the fold 60 forming one finished edge of the completed assembly, the other three

edges being open to permit the insertion of the heating assembly shown in FIGURE 4. The two power leads 40 and 42 are drawn through the tube 58, and the sub-assembly is inserted between the folded portions of the metal housing and is secured in place with dobs of Pliobond cement. The assembly is then spotwelded as at 62 with the flanges 54 of the folded sections of the metal housing carefully aligned. The assembly is then completed by seam welding the three open edges along the flanges 54 to form a hermetically sealed container. Final sealing of the assembly is effected by forcing a plastic substance 64 such as that sold under the trademark Permagum into the outer end of the tube 58 in surrounding relation with the cables 40 and 42. The assembly is then tested for leaks with air under water and the finish is applied. Finally the assembly is readied for use by bending the tube 58 to the configuration shown or any other configuration required to permit convenient installation of the unit. When the tube is bent, it is allowed to flatten to provide a strain relief.

While the unit may have any desired dimensions in a typical case, it is approximately 31 inches long, 9 inches wide and $\frac{3}{8}$ inch thick. The inner heating assembly is approximately $1\frac{1}{2}$ inches shorter and $\frac{3}{4}$ inch narrower than the outer metal envelope to permit the edges of the latter to be tightly sealed together by seam welding without adversely affecting the inner plastic assembly. In a unit of this size the spacing and distribution of the wires will be such that the total of length of wire accommodated in the unit is almost 50 feet, thus giving the unit large capacity and providing for uniform distribution of heat over the entire area of the unit.

The invention may be embodied in other specific forms without departing from the spirit or essential characteristics thereof. The present embodiment is therefore to be considered in all respects as illustrative and not restrictive, the scope of the invention being indicated by the

appended claim rather than by the foregoing description, and all changes which come within the meaning and range of equivalency of the claim are therefore intended to be embraced therein.

5 What is claimed and desired to be secured by United States Letters Patent is:

A weatherproof electrical pad heater comprising a flat grid of resistance wire arranged in a series of side-by-side lengths connected by U-bends, a pair of plastic sheets 10 adhesively secured together to enclose said grid, an outer rigid metal housing comprising a metal sheet having a central flat section surrounded by marginal flanges offset from the plane of said central section, said central flat section being slightly more than twice the width of said 15 plastic sheets and slightly longer than said plastic sheets, said metal sheet being folded double in surrounding relation with said plastic sheets to form a rigid envelope, said flanges being disposed outwardly beyond the marginal edges of said plastic sheets and being sealingly 20 secured together in waterproof relation, electrical leads extending through one of said plastic sheets and a portion of said flat section connecting said resistance wire to the exterior of said envelope, a tube rigid with said envelope enclosing said electrical leads and means sealing 25 said leads at the entrance to said tube.
